(57) **CLAIM**

The ornamental design for an electronic wrist device with band, as shown and described.

DESCRIPTION

FIG. 1 is a top front perspective view of an electronic wrist device with band showing our new design;

FIG. 2 is a top view thereof;

FIG. 3 is a bottom view thereof;

FIG. 4 is a front view thereof;

FIG. 5 is a rear view thereof;

FIG. 6 is a left view thereof; and,

FIG. 7 is a right view thereof;

The broken line showing of the wrist band is included for the purpose of illustrating the environmental structure and forms no part of the claimed design.

The dash-dot broken line(s) define the bounds of the claimed design and form no part thereof.
